UNITED STATES PATENT OFFICE.

WILLIAM J. KENNEY, OF WILMETTE, ILLINOIS, ASSIGNOR TO UNDER-FEED STOKER COMPANY OF AMERICA, OF CHICAGO, ILLINOIS, A CORPORATION OF NEW JERSEY.

UNDERFEED STOKER.

1,211,592.

Specification of Letters Patent. Patented Jan. 9, 1917.

Application filed October 10, 1914. Serial No. 866,028.

To all whom it may concern:

Be it known that I, WILLIAM J. KENNEY, a citizen of the United States, residing at Wilmette, county of Cook, and State of Illinois, have invented a certain new and useful Improvement in Underfeed Stokers, and declare the following to be a full, clear, and exact description of the same, such as will enable others skilled in the art to which it pertains to make and use the same, reference being had to the accompanying drawings, which form a part of this specification.

In burning high grade coking coals in self-cleaning underfeed stokers of the Jones type difficulty is sometimes experienced because of peculiar conditions which arise. Coal of this kind gives off its gases at a low temperature and the resulting coke is very hard and strong structurally. In the Jones stoker, the coal is fed forwardly and upwardly in a retort having twyer blocks around the top, the coal being coked as it rises and burns in the vicinity of the twyer blocks. The coke formed in the retort from ordinary coal readily yields to the pressure tending to force it upwardly and rearwardly and is broken up. In the case of high grade coking coal, the coke which is formed in the retort becomes a strong solid mass which fails to break up, thus preventing the air from the twyer blocks from being effectively distributed throughout the mass to be consumed, and resulting in the formation of blow holes in the fire. The various forces acting on the coke, such as the pressure of the incoming coal, gravity action due to the downward inclination of the top of the retort, and the mechanism at the side of the retort whose function is to feed the clinkers and ashes to the discharge passage, move the solid mass of coke rearwardly, and, because of the resistance encountered by the coke in such rearward movement, constantly increasing the closeness of its texture and its depth or thickness. The result is that combustion takes place even less readily and less effectively at the rear end of the retort than at the front end. The difficulties encountered are of course entirely due to the solidity of the coke and therefore, by breaking up the solid masses of coke, all advantages resulting from the use of the Jones type of stoker under the most favorable conditions of use are obtained with burning high grade coking coals.

The object of my invention is to provide a simple and effective means for automatically breaking up coke of any degree of hardness and strength which may be formed in the underfeed stokers of the Jones type or any other type embodying retorts or troughs into which the coal is fed.

The various features of novelty whereby my invention is characterized will herein-after be pointed out with particularity in the claims; but for a full understanding of my invention and of its object and advantages, reference may be had to the following detailed description taken in connection with the accompanying drawings, wherein:

Figure 1 is a longitudinal section taken through a retort equipped in accordance with the present invention; Fig. 2 is a section on line 2--2 of Fig. 1; Fig. 3 is a top plan view of the retort; and Fig. 4 is a perspective view of one of the twyer blocks.

Referring to the drawings, 1 represents the retort of the underfeed stoker, the inlet end of which projects through one wall, 2, of the furnace. The ram for feeding coal into the retort is not illustrated, but the auxiliary feeding mechanism consisting of the pusher rod in the bottom of the retort is indicated at 3. Around the top of the retort are twyer blocks, 4. In the usual arrangement, the inner faces of the twyer blocks are made continuations of the inner faces of the side walls of the retort. In accordance with my invention, I construct the twyer blocks so that they project inwardly beyond the inner surfaces of the side walls of the retort. In other words, the distance between twyer blocks on the opposite sides of the retort is less than the internal width of the top of the retort at the same point. Furthermore, the inner faces of the twyer blocks are so shaped that a row of the blocks on one side of the retort, viewed in plan, has the appearance of being provided with ratchet teeth on its inner edge, transverse shoulders of the teeth facing forwardly. In the arrangement shown, each block, viewed in plan, becomes narrower from the front end to the middle where it increases again in width so as to form a shoulder, 5, and then decreases again as the rear end is approached. Since the rear end of one block is narrower than the front end of the block just behind it, this leaves the front end of the latter block projecting so as to form a

shoulder similar to the shoulder, 5. Each block is also made shallower in the vertical direction at the rear end than at the front end so that a row of blocks in side elevation presents a broad edge made of long ratchet teeth whose abrupt faces face forwardly. The effect of this peculiar twyer block construction just described is as follows: The coking of the coal takes place in a zone below the twyer blocks and, as the coke is lifted and moved backward by the incoming coal beneath it, any solid mass which extends across the retort encounters a narrow passage as it engages with the twyer blocks in its upward movement and is subjected to transverse crushing stresses which break it up. At the same time the rearward movement between the twyer blocks on opposite sides of the retort brings into play a different set of crushing stresses which further aid in breaking up the mass. Whatever reaches the top of the twyer blocks and overflows thereon is subjected to crushing or tearing stresses, if it takes the form of a considerable mass, as the cleaning mechanism at the sides of the retort moves it toward the rear, over the irregular surface presented along the top of the twyer blocks. Consequently, any large body of coke that may be formed will be effectively broken up, so that the air will be distributed effectively by twyer blocks throughout the entire body of combustible material lying in the combustion zone, and the stoker will operate efficiently and at the full capacity regardless of the nature of the coal which is being burned.

Since the present invention does not de-

pend upon any particular kind of self-cleaning mechanism, I have not illustrated any self-cleaning mechanism, but direct attention to my prior application filed May 24, 1913, Serial No. 769564 for illustration of mechanism of this kind.

While I have illustrated and described in detail only a single preferred form of my invention, I do not desire to be limited to the structural details thus illustrated and described; but intend to cover all forms and arrangements which come within the terms employed in the definition of my invention constituting the appended claims.

I claim—

1. In combination, a retort open at the top and at one end and adapted to receive fuel through the open end, twyer blocks arranged about the top of the retort, the twyer blocks being shaped to produce a serrated inner edge containing a series of shoulders facing said open end.

2. The combination with the retort of an under-feed stoker, of twyer blocks arranged about the top of the retort, the twyer blocks being shaped to produce a serrated inner edge at the top of the retort, and the twyer blocks projecting inwardly from the upper edges of the retort and having their projecting under edges shaped to present a serrated line.

In testimony whereof, I sign this specification in the presence of two witnesses.

WILLIAM J. KENNEY.
